United States Patent Office.

JOHN EBLING, OF NEW YORK, N. Y.

Letters Patent No. 89,746, dated May 4, 1869.

IMPROVEMENT IN LOCKS.

The Schedule referred to in these Letters Patent and making part of the same.

To all whom it may concern:

Be it known that I, JOHN EBLING, of the city, county, and State of New York, have invented a new and useful Improvement in Locks; and I do hereby declare the following to be a full, clear, and exact description thereof, which will enable those skilled in the art to make and use the same, reference being had to the accompanying drawing, forming part of this specification, in which drawing—

Figure 1 represents a sectional view of the mechanism of this lock, when the same is open.

Figure 2 is a similar view of the same, when locked.

Figure 3 is a transverse section thereof.

Similar letters indicate corresponding parts.

This invention relates to a lock, the locking-device of which is acted on by a key, with a sectional stem, composed of two parts, which are hinged together, and operated by mere pressure on the ring, or handle of the key.

When the key is inserted in its socket, and its ring is compressed, the bits of said key are made to project through holes in the side of the socket, and if the bolt is locked, said bits act on projections of the tumbler or tumblers, so as to release the bolt, and allowing the same to follow the action of a spring, which forces it back into the case.

The same spring which acts on the bolt also acts on the latch, and the bolt is provided with one or more shoulders to act against a corresponding number of projections on the latch, in such a manner that by locking the bolt, the latch is also locked, but when the bolt is unlocked, the latch can be operated in the usual manner.

A represents the case of my lock, which is made of cast iron, or any other suitable material, in the usual form or shape.

In this case move the bolt B and the latch C.

The tail, or shank of the bolt is provided with a loop, or eye, a, which embraces the guide-rod D, and retains the bolt in its proper position, while it moves in and out.

On the rod D is wound a spiral spring, E, which acts on the loop a of the bolt, and also on an arm, b, which projects from the latch C, and embraces the rod D, so that by the action of one and the same spring, the bolt is forced back, and the latch is forced out.

The bolt is operated by a key, K, which is inserted into the socket F, and from this socket extends an arm, c, which, when the socket is turned in the direction of arrow 1, fig. 1, acts on a shoulder at the under side of the bolt, and forces the same out to the position shown in fig. 2.

In this position said bolt is retained by the action of one or more tumblers, G, which have their fulcrum on a stud, d, and the hooked tails, e, of which being acted on by a spring, g, drop into a notch, f, in the bolt.

After the bolt has been caught by the tumbler or tumblers, the socket F is returned to its original position by a spring, h.

From the outer end of the tumblers project pins i, which work in a groove, j, in the circumference of the socket F, and which, when said socket occupies its normal position, are opposite to holes k, which pass through to the interior of the socket, as shown in the drawing.

The key K is represented in fig. 3.

It is composed of two parts, which are united by a hinge-joint, l, and curved at one end, to form the ring, or handle m, while the straight ends of said two parts form the shank of the key.

A spring, n, which is enclosed in one part of the handle, and acts on the other part, presses the two parts of the shank together, and by compressing the ring against the action of the spring n, the two parts of the shank open like shears.

One portion of the shank is somewhat wider than the other portion, so that a cross-section of said shank is T-shaped, to correspond to the hole in the socket F.

In the interior of this hole is a projection, o, against which the shoulders p, of the shank of the key, catch up, so that said key, on being inserted into the key-hole, will be retained in the required position.

If the key is brought in this position, and the handle m is compressed, the pins, or bits q, which project from the narrow part of the shank, catch in the holes k of the socket, and bear against the pins i of the tumblers, provided the bolt is locked, and by these means the tumblers are tilted on their fulcrum, and the bolt is released, so that it is free to follow the action of its spring, and to fly back into the case.

It is obvious, that by changing the length of the bits q, and of the corresponding pins i, and by increasing the number of the tumblers, a lock can be produced, which is exceedingly difficult to open with any other instrument, except the proper key.

The bolt B is provided with shoulders r s, and if said bolt is locked, the shoulders r bear against the arm b, and the shoulder s against a lip, t, of the latch, and said latch is also locked, and it cannot be thrown back until the bolt is unlocked.

The latch is operated by a nut, L, and by knobs or handles, in the ordinary manner.

Having thus described my invention,

What I claim as new, and desire to secure by Letters Patent, is—

1. The key K, made in two parts, and provided with bits q, said parts being hinged together, and made to open by pressing the handle m, substantially as and for the purpose described.
2. The tumblers G, hinged to a stud, d, and provided with pins i, and hooked tails e, in combination with the socket F, key K, and bolt B, substantially as and for the purpose described.
3. The spring E, acting simultaneously on the bolt and on the latch, as shown and described.

JOHN EBLING.
